UNITED STATES PATENT OFFICE.

DANIEL M. WHITE, OF MALDEN, MASSACHUSETTS.

TUNING DEVICE.

SPECIFICATION forming part of Letters Patent No. 769,853, dated September 13, 1904.

Application filed December 15, 1903. Serial No. 185,284. (No model.)

To all whom it may concern:

Be it known that I, DANIEL M. WHITE, a citizen of the United States, residing at Malden, in the county of Middlesex and State of Massachusetts, have invented certain new and useful Improvements in Tuning Devices; and I do declare the following to be a full, clear, and exact description of the invention, such as will enable others skilled in the art to which it appertains to make and use the same.

This invention relates to tuning devices for pianos and other musical instruments.

The object of the invention is to improve the construction of tuning device shown and described in the Patent No. 521,688, granted to me June 19, 1894, and to provide a tuning device in which a rigid immovable tuning-pin is employed.

With this and other objects in view the invention consists of certain novel features of construction, combination, and arrangement of parts, as will be more fully described, and particularly pointed out in the appended claims.

In the accompanying drawings, Figure 1 is a side elevation of certain parts of a piano, showing the application of the invention, parts being in section to more clearly illustrate the construction. Fig. 2 is a top plan 25 view of the same. Fig. 3 is a vertical cross-sectional view showing the arrangement and manner of fastening the tuning-pins. Fig. 4 is a detail perspective view of a pair of tuning-pins. Fig. 5 is a similar view of one of the tuning-levers. Fig. 6 is a view similar 30 to Fig. 3, showing a different manner of securing the tuning-pins.

Referring more particularly to the drawings, 1 denotes the string-plate supported on 40 the head and foot blocks 2 2', which are supported by the wooden frame 2^a of the piano and arranged in the usual manner. On one end of the plate 1 are arranged pins 3 for holding the strings 4.

5 denotes the sounding-board, 6 denotes the bridge at one end of the strings, and 7 denotes the bridge at the opposite end of the same. The bridge 7 is formed on and is a part of the string-plate, and the sounding-board is mounted upon the supports 5', ar-

ranged on the frame 2^a, as shown. These parts may be of the ordinary or any desirable construction.

The opposite ends of the strings are connected to tuning-levers 8, which are arranged 55 adjacent to and bear or are fulcrumed against the base of the bridge 7. The free ends of the levers 8 are bent into the form of a hook 9 and engaged with threaded pins 10, which are rigidly connected with and project upwardly from the string-plate or the head-block, as shown. On the levers 8 are formed laterally-projecting perforated lugs 12, with which the ends of the wires are connected, and at their lower fulcrum edge or corner of 60 65 the levers they are provided with laterally-projecting strengthening-lugs 13. The pins 10 are arranged in their usual positions on the plate, and the levers 8 are slightly bent or offset to engage the same and to bring 70 each wire directly opposite or in alinement with the center of its pin. The pins 10 are preferably formed double and are substantially U-shaped, being connected together at their lower ends by a cross-piece 14. The upwardly-projecting portion of the pins are formed with two plain flat sides and two round threaded sides. The flat sides of the same are engaged by the hook-shaped ends of the tuning-levers 8, and the round threaded sides of 75 80 each pin are engaged by a nut 15, which bears on the top of the hook-shaped ends of the levers 8 and which when screwed up or down on the pins will adjust said levers and give the strings the required tension. The adjusting-nuts may be turned by the usual tuning key or hammer to adjust the levers. The hooked ends of the levers engage the pins on each flat side, thereby affording a firm bearing for the tuning-nut. The sides of the pins 90 engaged by the lever being flattened, friction between these parts will be avoided.

Instead of mounting the pins in the metal string-plate, as shown in Fig. 3, they may pass through enlarged openings in said plate 95 and be secured in the head-block or wooden frame of the piano, as shown in Fig. 6, thereby avoiding contact with the metal string-plate.

In order to diminish or prevent noise occa- 100

sioned by the rattling or interference of the levers, the same may be insulated from each other by means of pieces of felt, lead, cloth, leather, or other non-resonant material, as shown at 16.

The levers may be formed of cast metal or they may be stamped from heavy sheet metal and bent into shape, the string-connecting lugs 12 and the strengthening-lugs 13 being 10 cut or formed on the lever and bent at right angles to the same, as shown.

While the device has been shown and described in connection with a piano, it will be understood that the same may be applied to 15 other stringed musical instruments.

From the foregoing description, taken in connection with the accompanying drawings, the construction and operation of the invention will be readily understood without requiring a more extended explanation.

Various changes in the form, proportion, and the minor details of construction may be resorted to without departing from the principle or sacrificing any of the advantages of 25 this invention.

Having thus described my invention, what I claim as new, and desire to secure by Letters Patent, is—

1. The combination with a support having a bridge, of tuning-levers fulcrumed at one end against said bridge and having hook-shaped opposite ends, fixed threaded pins adapted to be engaged by the hook-shaped ends of said levers, and adjusting-nuts adapted to be 30 screwed onto said threaded pins and to bear on the hook-shaped ends of said levers whereby said levers are rocked to impart the desired tension to said strings, substantially as described.

2. The combination with a support having a bridge, of tuning-levers fulcrumed at one end against the base of said bridge and having hook-shaped opposite ends, fixed pins having two flat sides engaged by the hook-shaped ends 45 of said levers, the opposite sides of said pins being rounded and threaded, and adjusting-nuts adapted to be screwed onto the threaded portions of said pins to bear on the hook-shaped ends of said levers whereby said levers are rocked to impart to said strings the desired tension, substantially as described.

3. The combination with a support having a bridge, of tuning-levers fulcrumed at one end against the base of said bridge, and having hook-shaped opposite ends, a string-engaging lug and a strengthening-lug formed on said levers, double-threaded U-shaped pins fixedly mounted and adapted to be engaged by the hook-shaped ends of said levers, and adjusting-nuts adapted to be screwed onto the threaded ends of said pin to bear on the hook-shaped ends of said levers, whereby said levers are rocked to impart to said strings the desired tension, substantially as described.

4. The combination with a support having a bridge, of tuning-levers fulcrumed at one end against the base of said bridge, and having hook-shaped opposite ends, a string-engaging lug and a strengthening-lug formed on said levers, double U-shaped pins fixedly mounted 60 in said support, said pins having two oppositely-disposed rounded and threaded sides and two plain flattened sides, said flattened sides being engaged by the hook-shaped ends of said tuning-levers, and adjusting-nuts 70 adapted to be screwed onto the threaded portions of said pins to bear on the hook-shaped ends of said levers to rock the same and impart to said strings the desired tension, substantially as described.

5. A tuning device for stringed musical instruments having a fixedly-mounted double pin and rocking levers adjustably connected with said pin whereby the strings of said instrument may be given the desired tension, 85 substantially as described.

6. A tuning device for stringed musical instruments comprising a fixedly-mounted double, U-shaped pin, said pin having two oppositely-disposed flat sides and two rounded 90 threaded sides, adjusting-nuts adapted to be screwed onto the threaded portions of said pins, and means operated by said nuts, whereby the strings of said instrument are given the desired tension, substantially as described. 95

In testimony whereof I have hereunto set my hand in presence of two subscribing witnesses.

DANIEL M. WHITE.
